SIGNORS TO J. P. SÉEBURG PIANO COMPANY, OF CHICAGO, ILLINOIS, A CORPORA-
TION OF ILLINOIS.

AUTOMATIC PLAYER PIANO.

Application filed May 13, 1922. Serial No. 560,588.

The invention relates to automatic piano players and particularly to those of the coin controlled character.

It is a prime object of the invention to provide a device such as above referred to in which a plurality of record rolls, rewind rolls and a separate tracker bar for each set of record and rewind rolls, are employed and in which the record rolls may be selectively, successively or repeatedly played as desired, and rewound and brought to rest.

It is an additional object of the invention to provide a construction whereby a plurality of coins may be successively deposited in the machine and thereby automatically cause any one of said plurality of record rolls to be played, and rewound or repeated.

In addition to the above, it is an object of the invention to provide a structure which employs a single drive shaft to actuate all of said plurality of record and winding rolls; and in addition to provide an arrangement whereby the various driving mechanisms may be selectively, and consecutively moved from a neutral position to a driving position and to a rewinding position after the rendition of any one of the record rolls.

It is an added object of the invention to provide a selector mechanism which may be set to play any one of said plurality of record rolls and to combine with this selector mechanism, a controlling device which is operable to be set to cause a repetition of one of the selections, and which is also operable to selectively and consecutively play any of said record rolls.

It is a further object to provide a structure whereby the entire mechanism will be brought to rest after any particular selection has been rendered and to further automatically set the structure to replay any one of said plurality of selections after the rewinding operation has taken place.

In the particular structure illustrated in the drawings a coin controlled electric switch mechanism is employed which in turn controls an electric motor, the latter being provided to drive the various elements entering into the construction. This coin controlled switch mechanism is of a type which is operable by a single coin to cause a given selection to be rendered, re-

wound and brought to a rest and in addition is operable to permit the successive introduction of several coins, the first one of which causes a given selection to be rendered, the successive coins setting a certain portion of the switch mechanism so that after the rendition of a certain record, the same or another record will be automatically actuated.

After the playing of the last selection, this selection will be automatically rewound and the entire mechanism brought to a state of rest.

The mechanism which is operated by the coin controls a valve which is opened upon the deposition of a coin, causing the actuation of a pneumatic which releases the switch hereinbefore referred to, permitting it to close the circuit and cause the actuation of the motor and other mechanism under the control of said motor. The actuation of this pneumatic operates a certain setting mechanism which is actuated each time a coin is introduced into the machine, which will correspondingly actuate the setting mechanism and set it to prevent the release of the switch until a number of selections corresponding to the number of coins deposited have been played.

This setting mechanism includes another pneumatic which is operable after the rendition of each selection to actuate the setting mechanism and move it to effect a release or opening of the switch.

A ratchet wheel is employed in the setting mechanism which is provided with a detent or pin which is normally in contact with the switch and co-operates to hold the switch in an open position. Upon the insertion of a coin, the first mentioned pneumatic is operated, its action is transmitted to the ratchet wheel carrying the detent which moves the detent away from the switch permitting it to move to close the circuit. The arrangement is such that a plurality of coins may be successively introduced into the machine after a desired selection is brought into operation, and is such that each coin deposited actuates the aforementioned pneumatic and the ratchet wheel carrying the detent, each actuation of the ratchet wheel by this pneumatic increases the distance between the detent and

the switch arm which will thus necessitate the movement of the ratchet wheel in the opposite direction a distance equal to that which it was previously moved before the switch can be opened to bring the device at rest.

Upon the closing of the switch the various driving elements are brought into operation, which actuates a certain pump 10 to create a reduced air pressure. This reduced air pressure is communicated to a selector which may be manually set to selectively play any one of the plurality of record rolls which form part of the device.

15 This selector has co-operatively connected therewith, a setting device which is operable to be set to automatically cause a repetition of a previously selected record and may be set to automatically cause the playing of a 20 different selection upon the insertion of one or more coins in the machine.

This selector mechanism is provided with a plurality of tubular connections each one of which leads to a certain pneumatic which 25 is part of the driving mechanism for the player rolls.

This last mentioned pneumatic is caused to collapse when the proper connections are formed which cause the driving mechanism 30 to be moved from a neutral position to a driving position which thereby causes the record to be wound from the record roll. This driving of the record roll is continued until a port in the record is brought into 35 register with a port in the tracker bar which actuates another pneumatic and causes the driving connection between the driving mechanism above referred to and the winding roll to be released and automatically be brought into engagement with the record roll causing the latter to be actuated to rewind the record thereon.

The record is provided with another port 45 which is brought into register with a suitable port provided in the tracker bar which restores the driving mechanism to its neutral position, causing the electric switch to be actuated and opened and the entire mechanism brought to rest.

50 As before stated the switch mechanism is such that it may be set so that the driving mechanism will continue to operate after a certain selection has been played, this being accomplished by the introduction of several coins into the machine.

When the structure is set to accomplish 55 this last named advantage the switch will remain closed and depending upon the position of the setting mechanism, a repetition of the same selection or the playing of another selection may be automatically accomplished.

The structure for accomplishing this last 60 named result includes a pneumatic for actuating the selector. This selector being

rendered inoperative when the setting device is positioned to repeat a selection but is operable to actuate the selector when the setting device is set to automatically and consecutively play the various selections 70 confined in the instrument.

A locking mechanism is provided for locking the selector against being tampered with during the playing of any one of the plurality of record rolls. This locking mechanism 75 automatically releases the selector after any one of the plurality of record rolls has been played and thereby allows the selector to be shifted to cause the actuation of another of the record rolls contained in the 80 device.

The invention will be explained and more readily understood when read in conjunction with the accompanying drawings which illustrate one embodiment thereof, it being 85 obvious that changes and modifications may be resorted to without departing from the spirit of the appended claims forming a part thereof.

In the drawings Fig. 1 is a front elevation 90 of the uppermost portion of a piano player showing the relative arrangement of the tracker bars and the player and rewind rollers and the mechanism for causing the actuation thereof.

Fig. 2 is a fragmentary view showing more in detail a portion of the structure illustrated in Fig. 1.

Fig. 3 is a front elevation of another portion of the structure shown in Fig. 1.

Fig. 4 is a side view of the structure shown in Fig. 3.

Fig. 5 is a side elevation of the selection, selector, actuating and locking mechanism hereinbefore referred to.

Fig. 12 is a section similar to Figure 11 showing the parts in changed position.

Fig. 13 is a top plan view of a part of the player roll drive mechanism shown in Figure 2.

Fig. 14 is a partial sectional view of the structure shown in Figure 13.

Fig. 15 is a sectional view of a valve box 130 employed in the structure.

Figure 16 is a diagrammatic view showing the various devices employed and the tubular connections formed between them.

The arrangement contemplates the use of a plurality of sets of record and winding rolls and a tracker bar for each set, arranged in parallel tiers which are driven by a gear mechanism under the control of a pair of pneumatics which when actuated cause the gear mechanism to wind and rewind the record and to assume a neutral position when the rendition of the selection has been completed.

These sets of rolls, and tracker bars are generally designated 17, 18, 19, 20, 21 and 22 and each include the player roll 23, rewinding roller 24 and the tracker bar 25. The construction of one of these sets is identical with another and therefore an explanation of one will suffice for an understanding of the construction and operation of all.

The driving mechanism generally designated 26 includes a shaft 27 which is in jointed connection with the shaft 28 which carries a sprocket wheel 29 the latter of which is connected through the medium of a sprocket chain 30 with the sprocket wheel 31 of an adjoining driving mechanism which also includes a sprocket 32 and the sprocket chain 33 the latter of which is in turn associated with the sprocket 34 and is actuated by means of the sprocket 35 and the sprocket chain 36. This latter mechanism is driven by the sprocket wheel 37 carried by the main drive shaft 38. This shaft 38 is driven by the sprocket 39 and sprocket chain 40 which is actuated by the motor hereinbefore referred to.

This driving mechanism, bellows, and other associated devices employed may be of any desirable construction and therefore will not be referred to in detail herein.

The drive shaft 38 is provided with a sprocket wheel 41 which through the medium of the sprocket chain 42 is connected to the driving mechanisms of the various sets of player and rewinding rolls 20, 21 and 22 in a manner similar to that described in connection with the driving mechanisms of the sets 17, 18 and 19.

From the foregoing description it is evident that all of the driving mechanisms will be continuously driven during the playing and rewinding operation of any of the several sets of record and rewinding rolls.

The entire structure is under the control of the electric switch generally designated 43 and clearly shown in Figure 2. This switch is controlled by means of the lever 44 which engages the switch arm and is operable by a coin as the latter leaves the coin chute 45.

By referring to Figure 2 it is evident that upon the engagement of a coin and the lever 44 the valve 45 will be opened and the switch

arm 46 of the switch 43 will be permitted to move into contact with the contact element 47 and thereby close the circuit to the motor 48 which will cause the actuation of the various elements, such as the pump, and driving mechanism for the shaft 38. The valve 45 is connected by means of the tubular passage 49 with the valve box generally designated 50, shown in detail in Figure 15.

Upon the opening of the valve 45 air is admitted into the passage 49 which actuates the pouch 51 and closes the valve 52 which completes the connection between the reduced air chamber 53 of the valve box and the tubular passage 54 which terminates in a connection with the pneumatic 55 causing the collapse of the latter.

This pneumatic 55 carries the pawl 56 which engages the teeth 57 of the ratchet wheel 58 and causes the ratchet wheel 58 to be moved in a counter clockwise direction releasing the engagement of the pin 59 and the lowermost end of the switch arm 46, the latter of which is permitted at this time to be moved into contact with the contact element 47 by means of a spring such as 60.

When the switch arm 46 is in this last named position, the motor 48 is thrown into operation and the various elements under its control are actuated.

The lever arm 44 carries a pivoted element 61 which when the switch is open engages the uppermost end of the switch arm and holds it out of contact with the contact element 47, as illustrated in Figure 2. The pivoted element 61 permits the switch arm to be moved to allow it to open the switch when caused so to do by the pin 59 without affecting the lever arm 44 or the valve 45 and also permits the lever arm to be actuated by a coin without interfering with the closed condition of the switch.

Thus should one or more coins be inserted in the machine with the switch arm in closed position, the valve 45 may be opened and the pneumatic 55 actuated causing the distance between the lowermost end of the switch arm and the pin 59 carried by the ratchet wheel 58 to be increased step by step which will necessitate several actuations of

the pneumatic 62 to cause the pin 59 to be again brought into engagement with the lowermost end of the switch to thereby open the latter. This pneumatic 62 is connected by means of the tubular passage 63 with the valve box 50 and is operable after the completion of the playing of any one of

the several selections, to move the pin 59 toward the lowermost end of the switch arm. The pneumatic 62 is operated upon the register of a port in the record roll with a certain port provided in the tracker bar.

When the switch hereinbefore referred to is closed, the pumps, etc., are actuated which produces a reduced air pressure in

the reduced air chamber 64, Figure 16, which has the tubular passage 65 and 66 connected therewith.

The tubular passage 65 leads to a selector mechanism generally designated 67 and is clearly shown in Figures 5 to 8. This selector mechanism 67 is composed of two portions 68 and 69 which are held in contact with each other by means a coiled spring 69^a mounted upon the shaft 69^b which carries the rotor 68. The portion 68 is rotatable relatively to the part 69, it being rotatable to permit a connection to be formed between the passage 70 with one of the several ports 71 and the annular passage 72 carried by the stationary part 69.

This annular passage 72 has an extension 73 to which the tubular connection 65 extending from the reduced air chamber 64 is connected.

The rotatable portion 68 is provided with a segmental passage 74 having the port 75 which communicates with the atmosphere and will permit the introduction of atmosphere into all of the ports 71 excepting that port which is connected with the annular passage 72 through the medium of the passage 70.

Each of the passages or ports 71 are connected through the medium of a tubular passage such as 76 with the pneumatic such as 77 which is identical with other pneumatics provided to perform the same function for each set or record and winding rolls.

It is evident that when the connection between the passage 70 and any one of the ports 71 and passage 72 are completed, the respective pneumatic 77 connected with the particular port 71 will be collapsed allowing the portion 78 of the jointed shaft 27 to be lowered. To control the actuation or lowering of the drive shaft 27, a link connection 79 is provided between the pneumatic 77 and the shaft. The expanded condition of the pneumatic 77 normally holds this portion of the shaft 27 in a neutral position and upon the collapse of the pneumatic 77, the pinion 80 carried by the end of the shaft portion is permitted to engage the gear 81 and drive it, which will cause the record to be wound from the roll such as 24 to the roll 23.

The actuation of the roller 23 causes the playing of the selection carried by the roll 24.

The device continues to operate in this direction until a port in the record is brought into register with the port 82 provided in the tracker bar, the latter of which has a tubular passage 83 leading therefrom which terminates in a connection 84 (Fig. 14) below the pouch 85, it being understood that a bleed hole connection 86 is formed so as to provide a reduced air pressure in the tube 92 to which the passage 83 is connected.

This bleed hole connection is in communication with the reduced air chamber 87 which is connected to a reduced air chamber 64 through the tubular connection 88. Thus it will be evident that during the playing of a certain selection, a reduced air condition will exist in the passage 83 until the port 82 is opened to the atmosphere. The introduction of atmosphere into the passage will actuate the pouch 85 and the valve 89 close the aperture 90 and form a connection between the pneumatic 91 and the reduced air chamber 87.

The port 92 which is provided in one of the walls of the pneumatic 91 completes the connection between the pneumatic and the reduced air chamber 87 and causes the collapse of the pneumatic 91.

When the valve 89 is in its closed position, the reduced air condition existing in the chamber 87 will also exist in the passage 93 which will cause the collapse of the relatively small pneumatic 94 which due to the fact that the valve 89 is connected by means of the valve spindle to a part of the pneumatic 94, will hold the valve 89 closed until atmosphere is introduced into the tubular passage 95 which communicates with the port 96 in the tracker bar.

The object and purpose of this structure will hereinafter be explained in detail.

When the valve 89 is in its closed condition, the reduced air condition in the chamber 87 will cause the collapse of the pneumatic 91. This pneumatic 91 carries an arm 97 which extends below the movable portion 27 of the shaft and is designed to engage said shaft portion and move the latter upwardly upon the collapse of the pneumatic to which the arm is secured.

Upon the actuation or collapse of the pneumatic 91, the arm 97 lifts the shaft portion 27 and causes the disconnection of the pinion 80 and the gear 81 and produces a connection between the gear 98 intermediate gear 99 and the pinion 100, the latter of which is carried by the shaft of the rewind roll 24. This will cause the rewinding of the record to position it for replaying.

The record carried by the record roll is provided with another port which is adapted to register with the port 101 provided in the tracker bar 25. This last mentioned port and connections therewith are provided to actuate a cutoff mechanism which when actuated, brings the entire mechanism at rest.

The structure whereby the cutoff mechanism is actuated includes the tubular passage 102 which leads to a cutoff control box 103 which includes a plurality of pneumatics 104, one pneumatic 104 being provided for each set of player and rewind rolls and associated mechanism.

Each of the pneumatics 104 has a tubular connection 105 which leads to and termi-

nates in a connection with an opening 106 (Fig. 14) which will cause a reduced air pressure to exist in the passage 105 when the valve 89 is closed. This will cause the pneumatic 104 to collapse and simultaneously 5 actuate the slide valve 107 to connect the valve ports 108 and 109 together.

The valve port 109 is connected through the medium of the tubular passage 110 with 10 the passage 111 which terminates below the pouch 112 (Fig. 15) which, when actuated closes the valve 113 and completes the communication between the passage 114 and the reduced air chamber 53 and by virtue of the 15 tubular connection 63 between the passage 114 and the pneumatic 62, the latter will be actuated causing the dog 116 (Fig. 2) carried by the pneumatic 62 of the cutoff mechanism to engage the ratchet wheel 58 and 20 move the pin 59 into engagement with the switch causing the switch arm to be moved out of contact with the contact element 47 and bringing the entire device to a rest.

Upon the collapse of the pneumatic 104, 25 the valve 117 is opened permitting the introduction of atmosphere into the tubular passage 118 causing the actuation of the pouch 119 and the valve 120 which completes the communication between the passage 122 and 30 the pneumatic 123 causing the collapse of this pneumatic and the closing of the valve 124 preventing the reduced air pressure created by a pump (not shown), from affecting the various parts of the structure and 35 causing their actuation. This pump is connected by means of the tubular passage 125 with the reduced air chamber 64.

The closing of the valve 124 prevents the 40 reduced air condition existing in the chamber 64 from being transmitted to the player action which may be connected with the tubular connection 126. Upon the collapse of the pneumatic 123, the pneumatic 127 which is connected to the pneumatic 123 45 through the passage 128 is also caused to collapse also opening the valve 129 permitting the introduction of atmosphere into the chamber 130.

As before stated, during the rewinding action 50 of the record roll, the pneumatic 94 is collapsed and the valve 89 held closed thereby, due to the connection of the pneumatic through the passage 93 with the chamber 87 and should the structure be set for replaying or a repetition of the same selection, a 55 port in the record will be brought into communication with the port 96 which will permit the introduction of atmosphere into the tubular passage 95 which will allow the 60 pneumatic 94 to expand opening the valve 89 allowing atmosphere to enter the passage 92 of the pneumatic 91 and allow it to expand and by virtue of the connection between the port 106 and the tubular passage 65 105, the pneumatic 104 will again be caused

to expand moving the slide valve 107 out of connection with the passages 108 and 109 and simultaneously close the valve 117.

The closing of the valve 117 will cause the valve 120 to close likewise, which will 70 form an atmospheric connection between the passage 122 and the pneumatic 123 causing the opening of the valve 124 and allow the reduced air pressure created by virtue of the connection of the pump (not shown) 75 with the passage 125 to be completed through the connection 126 with the player pneumatics and to also exist in the passage 65 which leads to the selector generally designated 80 67.

The position of the parts of the selector will again cause the collapse of the pneumatic 77 and the connection between the pinion 80 and the gear 81 to be completed which 85 will cause the record to be driven from the rewinding roll to the player roll.

A mechanism whereby either a repeated or selective playing of the various record rolls may be accomplished is employed. This mechanism is clearly shown in Figures 90 3 and 4 and includes a movable valve block 131 which is movable by the knob 132 to cause repeated playing of a given selection or selective playing of the various musical 95 selections confined in the instrument.

The movable valve block 131 is arranged between the panel board 133 and the stationary portion 134, the latter of which is provided with a pair of passages 135 and 136. One of these passages such as 136 is attached by means of the tubular passage 66 which is T-tubed with tubular connection 122 with the chamber 53 of the valve box 50. The other passage such as 135 is connected through the medium of the tubular passage 137 with the pneumatic 138. Thus when the movable valve block is set for automatic or repeated playing and the valve 120 actuated by virtue of the operation of the pneumatic 104, a reduced air connection 110 is formed with the reduced air chamber 53, which through the tube 122 will actuate the pneumatic 123 which cuts out the player action and renders it inoperative. The 115 swinging leaf of the pneumatic 138 carries the pawl 139, the latter of which is successively brought into engagement with the pins 140 which extend from one face of the rotatable portion 68 of the selector 67 and consecutively move the passage 70 into communication with the various ports 71 when the valve block 131 is set to permit of this. 120

The valve block 131 is provided with a passage 141 which when set in the position shown in Figure 3 provides a communication between the tubular passages 66 and 137, and thus upon the termination of one piece and the insertion of another coin, the mechanism will be actuated. This tube 66 is connected 125 with the tube 122 which in turn is connected 130

to the valve 120 of the valve box 50. Thus upon the rewind of the record roll one of the several pneumatics 104 is actuated which opens its respective valve 117 permitting atmosphere to enter the tube 118 which actuates the valve 120 completing a communication between the reduced air chamber 53 and the tubular passage 122 causing the operation of the pneumatic 138 which moves the selector 67 to a position to cause the actuation of another record roll, should another coin be inserted. It will be remembered that the switch mechanism is such that several coins can be successively inserted into the machine which will automatically cause the winding roll of another record roll to be operated until the rewind port 82 is again opened to the atmosphere which will cause that pneumatic 104 associated therewith to be actuated which opens the valve 117 causing the reduced air condition previously referred to to exist in the passages 122, 66 and 137. This will cause the selector to again be actuated to set it to repeat the action just described.

The actuation of the pneumatic 138, causes the rotation of the rotatable portion 68 of the selector 67 which will successively bring the passage 70 into communication with the various ports 71 and as these ports 71 are each connected to a different set of player and rewind rolls, each of these sets will be consecutively brought into operation.

The foregoing operation will also be accomplished when a plurality of coins are introduced into the machine after one set of player and rewind rolls have been actuated, as it will be remembered that under the conditions just described the switch 43 remains closed until the pin 59 is brought into engagement therewith to open it.

If it is desired to repeat the playing of the selection the valve block 131 will be moved so that the connection between the tubular passages 66 and 137 is broken. This will prevent the collapse of the pneumatic 138 and causes the movable portion 68 of the selector to be retained in its previously adjusted position which will cause the repetition of the previously selected roll.

It is evident that with the valve block 131 in its last named position the rotatable portion 68 of the selector may be moved manually to cause the selective playing of any one of the plurality of record rolls confined in the machine. To permit of this the rotatable portion 68 is provided with the knob 148 which when actuated will also cause the passage 70 of the rotatable portion 68 to be brought into communication with one of the several ports 71 thereby permitting the device to be manually set to play any desired selection.

A locking mechanism is provided to lock the selector shown in Figures 5 to 8 against

movement after the playing of a selection has been started. This mechanism includes a pneumatic 143 which is normally extended. This pneumatic is designed to actuate the pivoted holding dog 144 to cause it to engage one of the various pins 140 carried by the rotatable portion 68 of the selector.

This dog 144 is connected to the swinging leaf of the pneumatic 143 through the medium of the link 145 and thus as the pneumatic is collapsed or extended the holding dog 144 will be brought into and out of engagement with the various pins 140. This pneumatic 143 may be connected through the tubular connection 146 to the tubular passage 65, which as before stated is during a certain period of condition of the mechanism connected with a source of reduced air pressure, as it is connected to the chamber 130.

From the foregoing description and explanation of the structure, it is evident that an arrangement is produced whereby one or more coins may be consecutively introduced into the machine and thereby cause a consecutive playing of the various music rolls.

It is also manifest that the device may be manually set to selectively play any one of the plurality of music rolls and further that the device is capable of being set so that the playing of any one of the various selections may be repeated.

What we claim is:—

1. In an automatic player of the character described the combination of a plurality of sets of player and winding rolls and a plurality of tracker bars one independent tracker for each set, driving mechanism for each set, a selector connected with all of said driving mechanisms, selectively to set any one of said driving mechanism to be operated to cause a player roll to be actuated to render a selection, means for automatically causing each winding roll to be actuated in the reverse direction, means for automatically causing the driving mechanism to be brought to a rest, and a setting mechanism co-operatively associated with the selector, said setting mechanism being operable to cause the automatic repetition of a selection previously rendered.

2. In an automatic player of the character described the combination of a plurality of sets of player and winding rolls and a plurality of tracker bars one independent tracker for each set, driving mechanism for each set, a selector connected with all of said driving mechanisms, to selectively set any one of said driving mechanism to be operated to cause a player roll to be actuated to render a selection, means for automatically causing each winding roll to be actuated in the reverse direction, means for automatically causing the driving mechanism to be brought to a rest, and a setting

mechanism co-operatively associated with the selector, said setting mechanism being operable to cause the automatic operation of the setting mechanism to cause a successive 5 actuation of the various player rolls.

3. In an automatic player of the character described the combination of a plurality of sets of player and winding rolls and a plurality of tracker bars one independent 10 tracker for each set, driving mechanism for each set, a selector connected with all of said driving mechanisms to selectively set any one of said driving mechanism to be operated to cause a player roll to be actuated to 15 render a selection, means for automatically causing each winding roll to be actuated in the reverse direction, means for automatically causing the driving mechanism to be brought to a rest, and a setting mechanism 20 co-operatively associated with the selector, said setting mechanism being operable to cause the automatic repetition of a selection previously rendered, and automatic operation of the setting mechanism to cause the 25 successive actuation of the various sets of player rolls.

4. In an automatic player of the character described the combination of a plurality of sets of player and winding rolls and a plurality of tracker bars one independent 30 tracker for each set, driving mechanism for each set, a selector connected with all of said driving mechanisms, to selectively set any one of said driving mechanism to be operated to cause a player roll to be actuated to 35 render a selection, means for automatically causing each winding roll to be actuated in the reverse direction, means for automatically causing the driving mechanism to be brought to a rest, and a setting mechanism 40 co-operatively associated with the selector.

5. In an automatic player of the character described the combination of a plurality of sets of player and winding rolls and a plurality of tracker bars one independent 45 tracker for each set, driving mechanism for each set, for driving and rewinding said rolls, a selector connected with all of said 50 driving mechanisms to selectively set any one of said driving mechanisms, means for actuating the driving mechanism to cause the rewinding of said music roll, a connection 55 between said means and the tracker bar for controlling the actuation of said means, and a cut-off device connected with said means.

6. In an automatic player of the character described the combination of a plurality of sets of player and winding rolls and a plurality of tracker bars one independent 60 tracker for each set, driving mechanism for each set, for driving and rewinding said rolls, means for actuating the driving mechanism to cause the rewinding of said 65

music roll, a connection between said means and the tracker bar for controlling the actuation of said means, a cut-off control device connected with all of said means, and a cut-off mechanism connected with said cut-off control device, said cut-off mechanism including a switch. 70

7. In an automatic player of the character described the combination of a plurality of sets of player and winding rolls and a 75 tracker bar for each set, driving mechanism for each set, for driving and rewinding said rolls, means for actuating the driving mechanism to cause the rewinding of said music roll, a connection between said 80 means and the tracker bar for controlling the actuation of said means, a cut-off control device connected with said means, a cut-off mechanism connected with said cut-off control device, a connection between the 85 cut-off control device and the tracker bar, and a valve controlling the connection leading from the cut-off control device and the tracker bar and the connection leading from the cut-off control device to the cut-off 90 mechanism, the latter including an electric switch.

8. In an automatic player of the character described the combination of a plurality of sets of player and winding rolls and a 95 tracker bar for each set, driving mechanism for each set, for driving and rewinding said rolls, means for actuating the driving mechanism to cause the rewinding of said music roll, a connection between said 100 means and the tracker bar for controlling the actuation of said means, a cut-off control device connected with said means, a cut-off mechanism connected with said cut-off control device, a selector, a connection between the cut-off control device and the 105 tracker bar, and means controlling the connection leading from the cut-off control device and the tracker bar and the connection leading from the cut-off control device to the cut-off mechanism, and means also controlling the operation of said selector. 110

9. In an automatic player of the character described the combination of player and winding rolls and tracker bar driving means for the player and winding rolls, said driving means being laterally movable to cause said rolls to be rotated to wind and rewind a record and be brought to a rest, means for moving said driving means to cause the winding and rewinding of the record, a selector, a connection between said means and the tracker bar whereby the driving means may be caused to be actuated to rewind the record roll, a cut-off mechanism, a cut-off control device, a connection between the cut-off control device and the tracker bar, a connection between the cut-off control device and cut-off mechanism, 115 and said cut-off control device being oper- 120

able to prevent the operation of said selector.

10. In an automatic player of the character described the combination of a plurality of sets of player and winding rolls and a tracker bar for each set, driving mechanism for each set, for driving and rewinding said rolls, means for arranging the driving mechanism to cause the rewinding of said music roll, a selector, a reduced air chamber with which the selector is connected, a connection between said means and the tracker bar for controlling the actuation of said means, a cut-off control device connected with said means, a cut-off mechanism connected with said cut-off control device, a connection leading from each of said tracker bars to the cut-off control device, a single connection leading from the cut-off control device to the cut-off mechanism, said cut-off control device including means connected with the reduced air chamber, said last mentioned means being operable to prevent the operation of said selector.

11. In an automatic player of the character described the combination of a plurality of sets of player and winding rolls and a tracker bar for each set, driving mechanism for each set, for driving and rewinding said rolls, means for arranging the driving mechanism to cause the rewinding of said music roll, a selector, a reduced air chamber with which the selector is connected, said selector having means whereby same may be set to selectively and repeatedly play a selection, a connection between said first mentioned means and the tracker bar for controlling the actuation of said first mentioned means, a cut-off control device connected with said means, a cut-off mechanism connected with said cut-off control device, a connection leading from each of said tracker bars to the cut-off control device, a single connection between said cut-off control device and the cut-off mechanism, and means for connecting one of said connections leading from the cut-off control device to the tracker bar with the connection leading to the cut-off mechanism.

12. In an automatic player of the character described the combination of a plurality of sets of player and winding rolls and a tracker bar for each set, driving mechanism for each set, for driving and rewinding said rolls, means for positioning the driving mechanism to cause the rewinding of said music roll, a setting mechanism, a connection between said means and the tracker bar for controlling the actuation of said means, a cut-off control device connected with said means, a cut-off mechanism connected with said cut-off control device, a connection leading from each of said tracker bars to the cut-off control device, a single connection between said cut-off control device and the

cut-off mechanism, and a valve for connecting one of said connections leading from the cut-off control device to the tracker bar with the connection leading to the cut-off mechanism, said cut-off control device being connected with the setting mechanism and providing means to cause the operation of the setting mechanism.

13. In an automatic player of the character described the combination of a plurality of sets of player and winding rolls and a tracker bar for each set, driving mechanism for each set, for driving and rewinding said rolls, means for positioning the driving mechanism to cause the rewinding of said music roll, a setting mechanism having a locking mechanism for preventing the actuation of the setting mechanism upon the actuation of the driving mechanism, a connection between said means and the tracker bar for controlling the actuation of said means, a cut-off control device connected with said means, a cut-off mechanism connected with said cut-off control device, a connection leading from each of said tracker bars to the cut-off control device, a single connection between said cut-off control device and the cut-off mechanism, and an automatically operable valve for connecting one of said connections leading from the cut-off control device to the tracker bar with the connection leading to the cut-off mechanism.

14. In an automatic player of the character described the combination of a plurality of sets of player and winding rolls and a tracker bar for each set, driving mechanism for each set, a selector connected with each driving mechanism to selectively set each driving mechanism to be independently operated to cause a player roll to be actuated to render a selection, a cut-off mechanism including an electric switch and a cut-off control device, a single connection leading from the cut-off control device to the cut-off mechanism, a connection leading from each of said tracker bars to the cut-off control device and means for connecting one of said connections leading from the cut-off control device to the tracker bar with the connection leading to the cut-off mechanism.

15. In an automatic player of the character described the combination of a plurality of sets of player and winding rolls and a tracker bar for each set, driving mechanism for each set, a selector connected with each driving mechanism to selectively set each driving mechanism to be independently operated to cause a player roll to be actuated to render a selection, a cut-off mechanism including an electric switch and a cut-off control device, a single connection leading from the cut-off control device to the cut-off mechanism, a connection leading from each of said tracker bars to the cut-off control device and a valve for connecting one of said

connections leading from the cut-off control device to the tracker bar with the connection leading to the cut-off mechanism.

16. In an automatic player of the character described the combination of a plurality of sets of player and winding rolls and a tracker bar for each set, driving mechanism for each set, a selector connected with all of said driving mechanism to selectively set each driving mechanism to be independently operated to cause a player roll to be actuated to render a selection, means connected with the selector for causing a selection to be played and rewound and to be repeated, a cut-off mechanism and a cut-off control device, a single connection leading from the cut-off control device to the cut-off mechanism, a connection leading from each of said tracker bars to the cut-off control device and an automatically operable valve for connecting one of said connections leading from the cut-off control device to the tracker bar with the connection leading to the cut-off mechanism.

25 17. In an automatic player of the character described the combination of a plurality of sets of player and winding rolls and a tracker bar for each set, driving mechanism for each set, a selector connected with all of said driving mechanism to selectively set each driving mechanism to be successively and automatically operated to cause a player roll to be actuated to render a selection, and rewound a cut-off mechanism and a cut-off control device, a single connection leading from the cut-off control device to the cut-off mechanism, a connection leading from each of said tracker bars to the cut-off control device and means for connecting each of said connections leading from the cut-off control device to the tracker bar with the connection leading to the cut-off mechanism.

18. In an automatic player of the character described the combination of a plurality of sets of player and winding rolls and a tracker bar for each set, driving mechanism for each set, a selector connected with all of said driving mechanism, means for automatically operating the selector to cause each driving mechanism to be independently operated, said selector having a stationary and rotatable element having means which cooperate with each other to complete a connection to cause a player roll to be actuated to render a selection, a cut-off mechanism and a cut-off control device, a single connection leading from the cut-off control device to the cut-off mechanism, a connection leading from each of said tracker bars to the cut-off control device and means for connecting one of said connections leading from the cut-off control device to the tracker bar with the connection leading to the cut-off mechanism.

65 19. In an automatic player of the char-

acter described the combination of a plurality of sets of player and winding rolls and a tracker bar for each set, driving mechanism for each set, a selector connected with each driving mechanism, said selector having a stationary and rotatable element having means which cooperate with each other to complete a connection to cause each driving mechanism to be operated to cause a player roll to be actuated to render a selection, said selector being manually operable to cause a selection to be played, automatically operable to repeat said selection and automatically operable to cause said rolls to be successively played and rewound, a cut-off mechanism, and a cut-off control device, a connection leading from the cut-off control device to the cut-off mechanism, a connection leading from each of said tracker bars to the cut-off control device and means for connecting one of said connections leading from the cut-off control device to the tracker bar with the connection leading to the cut-off mechanism.

20. In an automatic player of the character described the combination of a plurality of sets of player and winding rolls and a tracker bar for each set, driving mechanism for each set, a selector connected with each driving mechanism, means for automatically operating the selector to cause each driving mechanism to be selectively and successively operated to cause a player roll to be actuated to render a selection, means for rendering the operating means for the selector inoperative, whereby a repeated playing of a record roll may be accomplished, a locking means for preventing the actuation of the selector during the playing of a selection, a cut-off mechanism, and a cut-off control device, a connection leading from the cut-off mechanism, a connection leading from each of said tracker bars to the cut-off control device, and means for connecting one of said connections leading from the cut-off control device to the tracker bar with the connection leading to the cut-off mechanism.

21. In an automatic player of the character described the combination of a plurality of sets of player and winding rolls and a tracker bar for each set, driving mechanism for each set, for driving and rewinding said rolls, a selector for controlling the operation of the driving mechanism of each set, means connected with said selector for arranging the driving mechanism to cause the rewinding of said music roll, a locking mechanism for engaging the selector to prevent its operation during the playing of a roll, a connection between said means and the tracker bar for controlling the actuation of said means, a cut-off control device connected with said means, a cut-off mechanism connected with said cut-off control device,

a connection between the cut-off control device and the tracker bar, a connection between the cut-off mechanism and the cut-off control device and a valve controlling the 5 connection between the connection leading from the cut-off control device and the tracker bar and the connection leading from the cut-off control device leading to the cut-off mechanism, and means for actuating 10 said valve, upon the actuation of the driving mechanism to cause a rewinding of said music roll.

22. In a coin controlled automatic player of the character described the combination 15 of a motor, means controlling the motor, said means including a switch and means for controlling said switch, a plurality of sets of player and winding rolls and a plurality of tracker bars one independent tracker for 20 each set, driving mechanism for each set, a selector connected with each driving mechanism, to selectively set each driving mechanism to be independently operated to cause a player roll to be actuated to render a selection, means for automatically causing each 25 player roll to be actuated in the reverse direction, means for automatically causing the driving mechanism to be brought to a rest, a setting mechanism co-operatively associated with the selector, said setting mechanism being operable to cause the automatic repetition of a selection previously rendered, 30 said means for controlling said switch being operable to bring the motor at rest after the playing of a selection and being operable to permit the playing of a plurality of selections without affecting the motor.

23. In a coin controlled automatic player of the character described the combination 40 of a motor, means controlling the motor, said means including a switch and means for controlling said switch, a plurality of sets of player and winding rolls and a plurality of tracker bars one independent tracker for 45 each set, driving mechanism for each set, a selector connected with each driving mechanism, to selectively set each driving mechanism to be independently operated to cause a player roll to be actuated to render a selection, means for automatically causing each 50 player roll to be actuated in the reverse direction, means for automatically causing the driving mechanism to be brought to a rest, a setting mechanism co-operatively associated with the selector, said setting mechanism being operable to cause the automatic 55 operation of the setting mechanism to cause a successive actuation of the various player

rolls, said means for controlling said switch being operable to bring the motor at rest 60 after the playing of a selection and being operable to permit the playing of a plurality of selections without affecting the motor.

24. In a coin controlled automatic player of the character described the combination 65 of a motor, means controlling the motor, said means including a switch and means for controlling said switch, a plurality of sets of player and winding rolls and a plurality of tracker bars one independent 70 tracker for each set, driving mechanism for each set, a selector connected with each driving mechanism, to selectively set each driving mechanism to be independently operated 75 to cause a player roll to be actuated to render a selection, means for automatically causing each player roll to be actuated in the reverse direction, means for automatically causing the driving mechanism to be brought to a rest, a setting mechanism co-operatively 80 associated with the selector, said setting mechanism being operable to cause the automatic repetition of a selection previously 85 rendered, and automatic operation of the setting mechanism to cause the successive actuation of the various sets of player rolls, said means for controlling said switch being operable to bring the motor at rest after the playing of a selection and being operable to 90 permit the playing of a plurality of selections without affecting the motor.

25. In a coin controlled automatic player of the character described the combination 95 of a motor, means controlling the motor, said means including a switch and means for controlling said switch, a plurality of sets of player and winding rolls and a plurality of tracker bars one independent tracker for 100 each set, driving mechanism for each set, a selector connected with each driving mechanism, to selectively set each driving mechanism to be independently operated to cause 105 to be actuated to render a selection, means for automatically causing each player roll to be actuated in the reverse direction, means for automatically causing the driving mechanism to be brought to a rest, a setting mechanism co-operatively associated with the selector, said means for controlling said switch being operable to bring the motor at rest after the playing of a selection and being 110 operable to permit the playing of a plurality of selections without affecting the motor.
